UNITED STATES PATENT OFFICE.

EDWARD M. SMITH, OF FALL RIVER, MASSACHUSETTS.

FUEL-INJECTOR.

1,018,276.

Specification of Letters Patent. Patented Feb. 20, 1912.

Application filed July 20, 1909. Serial No. 508,668.

To all whom it may concern:

Be it known that I, EDWARD M. SMITH, a citizen of the United States, residing at Fall River, in the county of Bristol, State 5 of Massachusetts, have invented certain new and useful Improvements in Fuel-Injectors; and I do hereby declare the following to be a full, clear, and exact description of the invention, such as will enable others skilled 10 in the art to which it appertains to make and use the same.

This invention relates to improvements in internal combustion motors of the type known as crank-case compression engines and 15 the principal object of the invention is the provision of an injector adapted to deliver a quantity of combustible liquid into the by-pass of the motor upon the suction stroke.

Another object is the provision of a deflector adapted to direct a certain quantity 20 of air into a vaporizing cup upon the compression stroke of the motor.

With these and other objects in view as will more fully hereinafter appear, the present invention consists in certain novel details of construction and arrangement of parts, hereinafter fully described, illustrated 25 in the accompanying drawings and more particularly pointed out in the appended 30 claim; it being understood that various changes in the form, proportion, size and minor details of the device may be made without departing from the spirit or sacrificing any of the advantages of the invention. 35

In the accompanying drawings forming part of the specification:—Figure 1 is a side elevation of my improved device applied to a two-cycle internal combustion 40 motor, the latter being shown in vertical section. Fig. 2 is a detailed plan view of the device. Fig. 3 is an end view of the device. Fig. 4 is a detailed vertical sectional view of the device.

Similar numerals of reference are employed to designate corresponding parts throughout.

As shown in Fig. 1 the device is applied to a two-cycle internal combustion engine; 50 it must be understood however, that I am not to be limited to this specific application since it can be readily understood, from what will appear later, how the device can be equally as well applied to a four-cycle motor. The cylinder of the motor is designated by the numeral 5 and the crank case

by the numeral 6. The air-in-take valve of the crank case is designated by the numeral 7, the piston by the numeral 8, and the by-pass communicating with the compression 60 space of the cylinder and crank case by the numeral 9. The baffle or deflector on the upper end of the piston which is arranged to come directly in front of the outlet of the by-pass leading into the cylinder when the 65 piston has completed its downward stroke, is designated by the numeral 10, and the exhaust port located in the cylinder wall directly opposite the baffle 10 is designated by the numeral 11. Since these parts and their 70 operation are well known to those skilled in the art, a detailed description of the same need not be given.

The device forming the subject-matter of the present invention is designated in general by the numeral 12 and is threaded or otherwise secured in an opening in the wall of the cylinder communicating with the upper end portion of the by-pass 9. The injector proper consists of a casing designated 75 in general by the numeral 13. This casing is substantially right-angular in contour and circular in cross section. The horizontal portion of the casing is designated by the numeral 14 and the vertical portion which 80 depends from the lower side and adjacent the inner end of the horizontal portion 14 is designated by the numeral 15. The inner end of the horizontal portion 14 terminates 85 in an enlarged annular thickened head 16, 90 the inner face of which is under-cut to a point adjacent its middle so as to provide a circular plug 17 which is exteriorly screw threaded as shown at 18. The plug 17 is 95 designed to be threaded into a circular screw threaded opening formed in the wall of the cylinder and adjacent the upper end of the by-pass 9, as clearly shown in Fig. 1. The horizontal portion 14 is provided with an axial bore 19, and the vertical portion 15 is 100 similarly provided with an axial bore 20, the inner end of which communicates and terminates in the axial bore 19 of the horizontal portion. The bore 19 of the horizontal portion is, adjacent its outer end, 105 provided with a screw thread and threaded into the bore is a needle valve 21. It might here be stated that the inner end of the bore 19 extending through the horizontal portion 14 terminates in a converging opening, and 110 the inner end of the needle valve 21 which is provided with a tapered end nicely fits with-

in this opening, so that when the needle valve is turned the quantity of liquid flowing through the opening will be regulated according to the position of the needle valve 5 in the converging end of the bore.

Formed integral or otherwise secured to the inner face of the plug 17 is, what will subsequently be termed a vaporizing cup 22; this member is somewhat less in length 10 than the diameter of the plug 17 and is closed at either end by the end walls 23 and 24, as clearly shown in Fig. 2. The bottom of the cup curves upwardly and outwardly as shown at 25 and constitutes the outer side 15 of the cup, while the inner side is formed by the face of the plug 17, as clearly shown in Fig. 4. The middle of the cup is in axial alignment with the bore 19 of the horizontal portion 14 of the casing so that liquid passing through said bore will flow into the cup. In order to prevent the liquid from splashing upwardly and at the same time to provide a means for directing a current of air into the cup, a deflector 26 is employed. 20 This member is preferably formed of a single piece of sheet metal or the like and is of considerably greater length than the length of the cup 22. The opposite end portions of the deflector are bent at right-angles 25 as shown at 26' and 27 in Fig. 2 so as to provide end walls, and the upper side portion of the deflector is curved laterally and downwardly as shown at 28 and extends into the cup to a point adjacent the outlet of the 30 bore 19. It might here be stated that the end walls 26' and 27 are of greater width than the cup 22 and their inner edges are bent at right angles as shown at 29, so as to provide lugs, which have openings for 35 the reception of bolts or screws by means of which the deflector is fixedly secured to the inner face of the plug 17.

With this construction it is obvious that the side wall 30 of the deflector will be disposed in advance of the cup and that a space 40 will exist between the said vertical wall 30 and outer face of the cup. The curved portion 28 extending into the cup is spaced from the upper edge of the front wall 25 45 and is provided with incisions for the reception of the end walls 23 and 24 of the cup. As before stated, the plug 17 is threaded into an opening formed in the wall of the cylinder so that when the parts are 50 in position as shown in Fig. 1 the cup and deflector will be disposed in the by-pass 9 and adjacent the upper end thereof and it 55 can be readily seen that air passing upwardly through the by-pass will enter the space between the side wall of the deflector 60 and cup and be, by the curved portion 28 of the deflector, directed downwardly and into the cup, it being understood that the end of the curved portion 28 will be spaced 65 from the face of the plug 17 so that the air

will be permitted to escape upwardly and out of the cup as will be presently described.

The extremity of the portion 15 is externally screw threaded for engagement with the upper end of the coupling pipe 31, the 70 lower end of which communicates with the oil tank (not shown). Threaded into the lower end of the portion 15 is a sleeve 32, which extends to a point substantially intermediate of the lower end of the portion 15 and bore 19. The upper edge of this sleeve is beveled and forms a seat for a check valve 33. The check valve 33 is arranged to open upwardly and is held within its seat by a spring 34, which bears on a shoulder in the bore 20 and upper face of the valve 33.

In the operation of the device assuming that the parts are in position as shown in Fig. 1, and the piston begins its upward or suction stroke, the upward movement of the piston will create a partial vacuum in the crank case 6, whereby atmospheric pressure will force the in-take valve 7 of the latter inwardly causing air to enter into the crank case. A partial vacuum will likewise be formed in the by-pass 9 and this will lift the check valve 33, whereby the liquid in the tank (not shown) will be siphoned through the bores 20 and 19 and flow into the cup 22. On the downward or compression stroke of the piston, the air which has been sucked into the crank case will now be compressed and forced upwardly and into the by-pass 9 and thence a portion of the air will be deflected and directed into the cup 22 by the deflector 30. When the piston has reached the limit of its downward movement or compression stroke the in-take port of the cylinder will be uncovered by the wall of the piston, whereby the mixture of air and fuel will flow into the cylinder through the in-take port of the latter. It will be seen that air passing from the by-pass to the cylinder will when deflected, lift the liquid from the cup 22 and force the latter into the cylinder. It will be observed that during the compression stroke of the piston the valve 33 will be closed, thus preventing the liquid in the cup 22 from being forced back into the tank.

From the foregoing it can be seen that I have provided a device which is comparatively simple in structure and inexpensive to manufacture, embodying few parts and these so arranged that the danger of derangement will be reduced to a minimum. It will be observed that during the operation of the motor the cup 22 will be heated to a great extent, whereby the fuel will be more readily vaporized.

What is claimed as new, is:—

The combination of a cylinder having a piston therein, an air passage communicating with the cylinder and with a source of air supply, a fuel injector comprising a body

having a threaded plug at its inner end adapted to be screwed into a wall of the air passage, said body being provided with a needle valve passage extending longitudinally therethrough, a valve in the passage, a fuel passage communicating with the valve passage, a cup on the inner end of said screw plug into which the valve discharges, and a deflector comprising a vertical wall spaced from and extending across the outer side of said cup, an inclined wall curved inwardly

and downwardly from the upper edge of said vertical wall and overhanging said cup, said deflector being provided with end portions secured to the inner end of said screw 15 plug.

In testimony whereof, I affix my signature, in presence of two witnesses.

EDWARD M. SMITH.
